UNITED STATES PATENT OFFICE

VANCE S. FIRESTONE AND DELBERT SWARD, OF FREEPORT, ILLINOIS, ASSIGNEES TO
ARCADE MANUFACTURING COMPANY, OF FREEPORT, ILLINOIS, A CORPORATION
OF ILLINOIS

LATCH

Application filed February 16, 1929. Serial No. 340,422.

Our invention relates more particularly to latches for refrigerator doors.

One of our objects is to provide a construction of latch which will operate automatically without the use of springs which are objectionable, to lock the door by the mere act of closing the door and by which the more forcibly the door is swung toward closed position, the tighter the door will close.

10 Another object is to provide a construction operating as above stated and which shall comprise a single handle member for the unlatching and opening of the door.

15 Another object is to provide a latch construction comprising leverage means operating to effect the initial movement of the door toward open position to the end that such movement of the door may be effected with 20 the exertion of relatively slight force even though the door be in tightly closed position.

Another object is to provide a construction of latch device of the type automatically latching the door upon the act of swinging 25 the door to closed position which will be highly positive in its operation.

Another object is to provide for the operative positioning of the latch means on doors protruding different distances from 30 the outer face of the front wall of the refrigerator; and other objects as will be manifest from the following description.

Referring to the accompanying drawings: Figure 1 is a broken face view of the front 35 of a refrigerator structure containing an opening equipped with a door hinged thereto and provided with latch means for the door in accordance with our invention, the door being shown in tightly closed condition and the actuating lever being shown by dotted lines in one of the intermediate positions it occupies in the closing of the door.

Figure 2 is an edge view of the structure of Fig. 1 showing the door in tightly closed 40 position.

Figure 3 is an edge view of the same construction showing the door almost completely closed and with the parts of the latch device in a position corresponding thereto.

50 Figure 4 is a plan sectional view taken

through the structure of Fig. 1 at the latching mechanism thereof with this mechanism shown in plan and the door in slightly open position; and

Figure 5, a section taken at the line 5 on 55 Fig. 3 and viewed in the direction of the arrow.

In the drawings:

6 represents a refrigerator structure containing an opening 7 in its wall, and 8 a door 60 forming a closure for said opening and hinged to the structure 6 as represented at 9 and in accordance with common practice.

The particular illustrated embodiment of our invention comprises a keeper 10 for attachment to the outer face of the structure 6 adjacent the side of the opening 7 opposite that at which the door 8 is hinged, this keeper comprising a plate 11 at which it is attached to the structure 6, as by screws 12; a forwardly projecting portion 13 having a depending extension 14 presenting at its forward extremity a rearwardly and downwardly curved surface 15 and, to the rear of said surface, an upwardly and rearwardly 75 inclined cam-forming, or wedge, surface 16; and means connecting plate 11 and portion 13 together to provide for relative adjustment of these parts for a purpose hereinafter stated, these means comprising a forwardly projecting post 17 rigid with the plate 11; a head 18 from which the part 13 projects and containing a recess 19 into which the forward end of the post 17 extends and at which these parts are relatively adjustable; and a screw 20 80 passing through a slot 21 in the head 18 and screwed into an opening 22 in the post 17.

The latch mechanism also comprises a latch bolt 23 in the form of a lever pivotally connected between its ends at 24 to a plate 25, 85 the plate 25 being attached to the face of the door 8 adjacent the keeper above described, by screws 26. The bolt 23 presents the handle portion 27 which is deflected outwardly to extend in spaced relation to the door 8 as shown 90 in Fig. 4 and by which the unlatching of the door and the opening of the latter is effected. The pivoting of the bolt 23 is on a substantially horizontal axis whereby this bolt swings in a plane substantially parallel with 100

the face of the door 8 and the end thereof opposite the handle portion 27 and represented at 28 is provided for latching with the keeper above described, the bolt 23 being also 5 provided with a lug 29 extending laterally therefrom and in an upward direction, assuming the bolt to be in the full line position shown in Fig. 1.

The latch mechanism also comprises a 10 detent represented at 30 and pivoted on a substantially vertical pin 31 mounted in the walls of a recess 32 provided in the head 18, the detent 30 extending into this recess and thus adapted to rock in a substantially horizontal plane.

The detent 30 is of general bell crank form 15 as shown providing the angularly disposed arms 33 and 34 with a heel portion 35. The heel portion 35 is provided for abutment against the plate to limit rotation of the 20 detent clockwise in Fig. 4; the arm 34 is provided for cooperation with the lug 29 on the bolt 23; and the arm 33 is provided for cooperation with a lug 36 formed rigidly on the 25 plate 25, the arm 33 also cooperating with the head 18 to limit rotation of the detent in counterclockwise direction in Fig. 4, the side surface of the arm 34 adjacent the lug 29 on the bolt being curved forwardly and to the left in Fig. 4 as represented at 37.

The arrangement of the parts shown and described is such, as shown, that assuming the door to be open, the swinging of the door toward closed position causes the end portion 38 of bolt 23 (if this bolt occupies such a position about its pivot that its portion 28 overlaps the keeper) to ride against the cam surface 15 of the keeper thereby causing the bolt 23 to be rotated in counterclockwise direction in Fig. 1 to a position in which it 35 clears the lower extremity of the keeper. As the door nears closing position the lug 29 strikes against the curved surface 37 of the detent 30 the impact resulting therefrom 40 forcibly rotating the bolt 23 in clockwise direction in Fig. 1 which causes the bolt portion 28 to travel up the inclined surface 16 of the keeper and firmly force the door inwardly to closed position shown in Fig. 2, it 45 being understood from the foregoing that the greater the force applied by the operator in closing the door the more tightly the parts of the latch mechanism interengage for forcing the door to closed, latched, condition, it 50 being further understood that if the bolt 23 in the closing of the door does not extend at its portion 28 in overlapping relation to the keeper the lug 29 will nevertheless engage the surface 37 of the detent with the result 55 above explained.

In the closing of the door the lug 36 on the door engages the arm 33 of the detent 30 rocking the latter in counterclockwise direction in Fig. 4 to a position in which the arm 34 extends into the path of movement

of the lug 29 of the bolt 23 when this bolt is rotated, by the operator, in counterclockwise direction in Fig. 1 for unlatching the door.

To open the door the operator grasps the handle portion 27 of the bolt 23 and rotates this bolt in counterclockwise direction in Fig. 1 for downwardly swinging the portion 28 of this bolt out of interlocking engagement with the keeper, the lug 29 engaging the arm 34 of the detent in this operation as above stated and as the operator continues to rotate the bolt the detent 30 is rotated by the bolt in clockwise direction in Fig. 4, the arm 33 of the detent 30 exerting outward pressure against the lug 36 with the result of initially opening, or cracking, the door as shown in Fig. 3, in which position the bolt 23 is entirely clear of the keeper and the operator by merely pulling outwardly on the bolt swings the door from the initial open position to the final open position desired.

It is preferred that the several parts be so constructed and arranged as shown that the lug 29 of the bolt 23 will engage the surface 37 of the detent, in the closing movement of the door, before the lug 36 engages the arm 33 of the detent.

The feature of providing the keeper in sections adjustable relative to each other is desirable inasmuch as it permits of the use of the latch mechanism on structures, the doors of which extend at different distances from the outer surface of the casing wall when the door is in closed position and further permits of relatively fine adjustment of the shoulder surface 16 of the keeper relative to the cooperating end portion 28 of the bolt 23.

While we have illustrated and described a particular construction embodying our invention, we do not wish to be understood as intending to limit it thereto as the same may be variously modified and altered without departing from the spirit of the invention.

What we claim as new, and desire to secure by Letters Patent, is:

1. A latch mechanism for a door adapted to close an opening in a casing, said latch mechanism comprising a keeper on said casing, a latch bolt on said door for interlocking with said keeper, a detent pivoted on the wall of said casing and a member movable with the door engaging one portion of said detent when the door is closed, said detent in the closed position of the door extending at another portion thereof into the path of movement of said bolt in the movement of the latter toward unlatching position, whereby said movement of said bolt operates to effect initial opening movement of the door.

2. A latch mechanism for a door adapted to close an opening in a casing, said latch mechanism comprising a keeper on said casing, a latch bolt pivoted on said door for interlocking with said keeper, a detent pivoted on the wall of said casing and a mem-

ber movable with the door engaging one portion of said detent when the door is closed, said detent in the closed position of the door extending at another portion thereof into the path of movement of said bolt in the movement of the latter toward unlatching position, whereby said movement of said bolt operates to effect initial opening movement of the door.

3. A latch mechanism for a door adapted to close an opening in a casing, said latch mechanism comprising a keeper on said casing, a latch bolt pivoted on said door for interlocking with said keeper, a detent pivoted on the wall of said casing and a member movable with the door engaging one portion of said detent in the open position of said door, said detent extending at another portion thereof into the path of movement of said bolt in the movement of the door toward closed position and in the closed position of the door extending at a portion thereof into the path of movement of said bolt in the movement of the latter toward unlatching position, whereby in the closing of the door said bolt is forcibly swung toward latching position, and in the movement of the bolt to unlatching position said door is initially opened.

4. A latch mechanism for a door adapted to close an opening in a casing, said latch mechanism comprising a keeper on said casing, a latch bolt pivoted on said door for interlocking with said keeper, and a detent of general bell crank form pivoted on the wall of said casing and so positioned that in the closing of the door a part of the door engages one of the arms of said detent and moves the other arm thereof into the path of movement of the bolt when the latter is swung to unlatching position, for the purpose set forth.

5. A latch mechanism for a door adapted to close an opening in a casing, said latch mechanism comprising a keeper on said casing, a latch bolt pivoted on said door for interlocking with said keeper, and a detent of general bell crank form pivoted on the wall of said casing and so positioned that in the closing of the door said bolt engages one of the arms of said detent and the bolt is rocked thereby toward latching position and the other arm of said detent is engaged by a part of said door and rocks said detent into a position in which said first-referred-to arm extends into the path of movement of the bolt when the latter is rocked in a direction for unlatching the bolt.

6. A latch mechanism for a door adapted to close an opening in a casing, said latch mechanism comprising a keeper on said casing, a latch bolt for interlocking with said keeper and pivoted on said door to swing in a plane substantially parallel with the face of the door, a detent pivoted on the wall of said casing and a member on said door en-

gaging one portion of said detent when the door is closed, said detent in the closed position of said door extending at another portion thereof into the path of movement of said bolt in the movement of the latter toward unlatching position, whereby said movement of said bolt operates to effect initial opening movement of the door.

7. A latch mechanism for a door adapted to close an opening in a casing, said latch mechanism comprising a keeper on said casing, a latch bolt pivoted on said door for interlocking with said keeper, a detent of general bell crank form pivoted on the wall of said casing and so positioned that in the closing of the door said bolt engages one of the arms of said detent and the bolt is rocked thereby toward latching position and the other arm of said detent is engaged by a part of said door and rocks said detent into a position in which said first-referred-to arm extends into the path of movement of the bolt when the latter is rocked in a direction for unlatching the bolt, the parts being so constructed and arranged that in the closing of the door the bolt engages the detent before the latter is engaged by the door.

8. A latch mechanism for a hinged door comprising a keeper, a pivoted bolt for interlocking with said keeper, a pivoted detent, and a member engaging one portion of said detent in the closing movement of the door, said detent in the closed position of the door extending at another portion thereof into the path of movement of said bolt in the movement of the latter toward unlatching position, whereby said movement of said bolt operates to effect initial opening of the door.

9. A latch mechanism for a door adapted to close an opening in a casing, said latch mechanism comprising a keeper on said casing, a bolt pivoted on said door for interlocking with said keeper, a detent pivoted on said keeper and a member on said door engaging one portion of said detent when the door is closed, said detent in the closed position of said door extending at another portion thereof into the path of movement of said bolt in the movement of the latter toward unlatching position, whereby said movement of said bolt operates to effect initial opening movement of the door.
